ALPHONSE FERNANDEZ, OF WASHINGTON, DISTRICT OF COLUMBIA.

ALARM DEVICE.

1,254,786.

Specification of Letters Patent. Patented Jan. 29, 1918.

Application filed December 7, 1915. Serial No. 65,571.

To all whom it may concern:

Be it known that I, ALPHONSE FERNANDEZ, a subject of the King of Spain, residing at Washington, in the District of Columbia, have invented certain new and useful Improvements in Alarm Devices, of which the following is a specification.

This invention relates to an alarm device more particularly of that type which employs means for detonating a cartridge when the device is operated from a set condition.

One object of the present invention resides in providing a device of the above mentioned character which is novel in operation in that the trigger operating element may be moved universally.

Another object resides in providing a discharge receiving chamber having an abutment disposed in the direct path of the discharged gases and having an outlet substantially parallel to the axis of the discharge receiving chamber, thus preventing the possibility of ignition of exterior objects by the fire of the discharge.

A still further object consists in the novel arrangement of legs for supporting the device.

With the above and other objects in view, I will now proceed to describe one specific form of the device as herein illustrated for the purpose of explaining the principles of this invention.

In the drawings:

Figure 1 is a central section longitudinally of the device, taken substantially upon line X—X of Fig. 5,

Fig. 2 is a sectional view on the line 2—2 of Fig. 1,

Fig. 3 is an end view of the device,

Fig. 4 is a sectional view on the line 4—4 of Fig. 1,

Fig. 5 is a sectional view on the line 5—5 of Fig. 1,

Fig. 6 is a sectional view on the line 6—6 of Fig. 1,

Fig. 7 is a perspective view of the hinged member closing the compartment receiving the cartridge chamber.

Fig. 8 is a sectional view on the line 8—8 of Fig. 6,

Fig. 9 is a transverse sectional view taken through the firing lever and illustrating the notch therein to be engaged by a pawl to hold the lever in retracted position.

In detail:

The device comprises a substantially cylin-

drical casing A divided into compartments 1 and 2 by means of a partition 3. The former compartment is what may be termed the trigger mechanism compartment whereas the latter is what may be termed the cartridge chamber compartment. Superposed on the cartridge chamber compartment and integral therewith is the discharge receiving chamber 4 which receives, through the barrel opening 5, the direct discharge of the gases when a cartridge is fired. Directly opposite the passage 5 is located the end wall 6 of the chamber and hence the discharge takes place directly against this end wall. Alongside of and integral with this discharge receiving chamber is a passage 7 which, by means of a right angular passage 8 connects with the chamber 4 and thus an outlet for the gases is provided which has its axis substantially parallel to the axis of the passage 5 and to the axis of the chamber 4 and by reason of its location provides an indirect passage for the discharged gases. The advantage of this is that, provided any particles of metal or the like were accidentally included within the cartridge the same will be discharged against the solid abutment wall 6, and further by reason of the fact that the outlet for the discharged gases is indirect flame will not issue directly from the chamber 4 and thus the danger of producing conflagration when the device is operated is entirely eliminated.

Within the compartment 2 is located the rotatable cartridge chamber 9, which has a plurality of apertures 10 to receive the cartridges which are located in substantially radial directions from the center of the chamber 9. This chamber 9 is pivoted for rotation at 10°—10° and on its bottom carries the lugs 11 equal in number to the number of cartridges accommodated by the cartridge chamber 9. The head of the compartment 1 is apertured as at 12 directly in alignment with the passage 5 for purposes which will be hereinafter described. One side of the compartment 2 is open and one edge has pivoted thereto at 13 the side of a semi-circular member 14 which closes the side of the compartment 2 and is also provided with arms 15 which carry journals 10' for the cartridge chamber 9, and thus the cartridge chamber 9 may be swung out for re-loading. This member 14 is held, in its closed position, by means of a latch 16 which engages therewith, said latch being

carried on the shank 17 which is mounted for reciprocatory movement in brackets 18 carried by the wall of the compartment 1; the lower end of said shank 17 being provided with the lug 19 having the inclined face 20 which is adapted to be engaged by a similarly inclined face 21 of a lug 22 carried by a shank 23 journaled for reciprocation in the wall of the compartment 1 and having its knobbed end 24 projecting exteriorly of the casing, the shank of the latter member being at right angles to the shank 17. The button 24 is held in its outer position by means of a spring 25 which has one end attached to the lug 22 and the other end attached to the casing, said spring being a tension spring and therefore drawing the face 21 back out of engagement with the face 20 of the member 19 until the button 24 is pressed, at which time the said faces engage and by reason of their inclined nature this action serves to disengage the latch 16 from the member 14 after which the latter member is permitted to swing outwardly.

Within the compartment 1 and carried by the pivot pin 26 is a bell crank lever 27 which, at the end of the long arm carries the cartridge firing pin 28 which is adapted to project through the aperture 12. The long arm 27', at its end, has connected therewith at 29 a lever 30 which is slotted as at 31 to accommodate a pin 32 carried by the member 33 terminating in a knob 34 exteriorly of the casing; this being for the purpose of resetting the trigger member when it has once been actuated and the slot 31 provides for normally maintaining the member 34 in its usual position as shown in Fig. 1 even though the trigger mechanism be set or unset, by reason of the fact that the pin 32 is slidable in the slot 31. The long arm of the bell crank lever 27 is provided with a lug 35 in which the end of a leaf spring 36 is held, the other end being secured at 37 to the side wall of the compartment 1, said spring acting to bring the firing pin member 28 into forcible contact with the detonating cap of the cartridge when the trigger mechanism is operated from a set position.

The trigger mechanism consists of the shaft 36' which is reciprocable within a suitable bearing as shown, and carries at its forward end the latch 37' beveled as shown at 38, which when set, seats in a suitable slot or notch provided in the long arm of the bell crank lever 27. The shaft 36' has affixed thereto adjacent its rear end, arms indicated generally at 39, which extend radially from the shaft at approximately right angles to each other. By moving any of the arms in a rearward direction, the shaft 36' will be retracted and the latch 37' will be withdrawn from engagement within the slot or notch in the lever 27; whereupon the latter will be moved forwardly under impulse of the

spring 36, and the firing pin 28 will contact and explode the cartridge alined with the opening 12. An expansion spring 40 encircles the shaft 36' and bears at its forward end against a collar 41 carried by or affixed to the said shaft, and seats at its rear end against the collar 42 loosely inclosing and independent of the shaft, the said collar 42 being held stationary by conventional brackets indicated at 100. The spring thus normally forces the shaft forwardly to position the latch 37' in the path of travel of the notched portion of the lever 27'.

A tilting bracket 43 is associated with the arms 39 for retracting the shaft 36', and comprises bars crossed in the manner shown. This bracket lies close to the arms 39, and is adapted to have its bar ends or lateral extensions 39' engage the arms 39 when tilted, to force the member 39 rearwardly to withdraw the latch shaft against the tension of the spring 40. Secured to the bracket 43 and projecting forwardly therefrom is a lever 46', which is pivoted intermediate its ends as at 48 to a yoke or block 47, the latter being mounted for oscillation upon pins 47' extending from the ends thereof and supported by a post 75, (Fig. 5). This arrangement is such that tilting of the bracket in right angular directions may be made, the block being capable of oscillating in a direction at right angles to the direction of movement of the lever 46'.

Pivoted as at 45' to the forward end of the lever 46', is the inner end of a trigger rod 44. This rod is mounted for sliding movement inwardly and outwardly of the casing A in a block 45, the latter having laterally extending arms 46 journaled at their ends in suitable bearings 77, and being capable of oscillating vertically within the casing. The block 45 is also provided with a vertically disposed slot as indicated by dotted lines in Fig. 2, so that the rod 44 may move horizontally within the said block. A coil spring 48' encircles the trigger rod as shown, and bears at its forward end against a collar 49 fixed to the rod, and at its opposite end against the block 45. The rear end of the trigger rod extends through the opening 50, and beyond the casing, and is adapted to be engaged and moved to actuate the trigger and firing mechanism. From this description, it is seen that inward and outward sliding movement of the trigger rod will turn the lever 46' upon its pivot, whereupon the ends of the horizontally disposed bars of the tiltable bracket will operate to force the arms 39 upwardly, and the latch 37' will be withdrawn. Should the trigger rod be moved laterally, the same will rock upon the arms 46, and the lever 46' will oscillate in a similar direction, whereupon the vertically disposed bracket arms will operate upon the similarly disposed shaft arms to

move the shaft rearwardly, (see Fig. 5). Upon releasing the trigger rod the springs 40 and 48' will operate to force the parts to normal position.

5 In order to hold the member 44 in a central position in the opening 50 through which it projects a spring 51 is provided which has one end in connection with the member 44 and the other end connected 10 with a bracket 52 carried by the wall of the compartment 1.

The short arm of the bell crank lever has pivoted thereto at 53 an angular lever 54 the end of which extends through an opening 55 in the head end of the compartment 1, and engages with the lugs 11 carried by 15 the cartridge chamber 9. The end of this angular lever 54 is provided with a pawl 55 which acts, when the lever 27 is actuated, to move the cartridge chamber 9 in one direction continuously in a step by step movement; the cartridge chamber being latched in said position by a latch 56 carried in lugs 57 and held in an inward position 20 in engagement with lugs 11 by means of a spring 58, said latch 56 having an inclined surface 57' which is engaged by the lugs 11 to let the latter by-pass in one direction and to prevent the same from moving in a backwardly direction. The co-operation of the pawl 55 and latch 56 holds 25 the cartridge chamber 9 in a set position. The angular arm 54 is held in its normal position by means of the spring 59 mounted 30 at 60 on the short arm of the bell crank lever and bearing against the angular arm 54. The exterior of the casing A is provided 35 at 61 with a gimlet screw 62, which may be screwed into the floor or the like 40 to set the device in an operative position. Also the exterior of the casing A is provided with brackets 63 which have pivoted thereto at 64 the legs 65 which are nothing more than segments of a circle and therefore 45 may be rotated to the position shown in dotted lines in Fig. 1 to insure the legs against catching when the device is placed in the pocket for carrying the same.

The device is particularly adapted for 50 use by commercial travelers or the like who have occasion to occupy rooms as transients and are subject a great many times to theft. The device in its operation is either screwed or set on the floor adjacent the floor of the 55 room with the end 66 of the trigger operating element 44 in such a position that if the door is moved the member 66 will be engaged and in that way the device actuated. It will be seen, that by reason of the construction of the trigger operating mechanism, it is sensitive to the slightest movement and though it is only just touched the device will be operative.

In resetting the device the member 34 is 60 pulled upward which raises the bell crank

lever 27 into set position whence it is engaged by the latch 37. This also actuates the angular arm 54 so that it moves the cartridge chamber 9 around to bring another cartridge into position. 70

When reloading the device it is only necessary to uncatch the latch 16 by pressure on the button 24 whence the member 14 may be swung outwardly carrying with it the cartridge chamber 9 which may be then 75 rotated suitably to reload the same with cartridges.

While in the foregoing and in the drawings I have illustrated a specific embodiment of the present invention it is nevertheless to be clearly understood that this embodiment is illustrated merely for the purpose of explaining the principles of the device and I do not limit myself to such embodiment except in so far as the invention 85 is defined in the appended claims.

I claim:

1. In an alarm device, a firing mechanism including a firing pin, a latch for holding said pin retracted, arms in connection with 90 said latch, a bracket capable of tilting in directions at an angle to each other and adapted when tilted to engage said arms to move the same and said latch to retracted position, a trigger rod mounted for sliding and 95 oscillatory movement, and a connection between said rod and said bracket.

2. In an alarm device, a firing mechanism including a firing pin, a latch for holding said pin retracted, a lever capable of oscillating in directions at right angles to each other, a bracket on said lever, arms in connection with said latch and adapted to be engaged by said bracket, and a trigger rod connected to said lever. 100

3. In an alarm device, a firing mechanism including a firing pin, a bell crank lever supporting said pin and being provided with a notch, a shaft mounted for sliding movement, a latch on said shaft adapted to 110 engage in said notch to hold said bell crank in cocked position, a spring on said shaft for holding the same extended, arms fixed to said shaft, a lever capable of swinging horizontally and vertically, a bracket secured to said lever and having arms adapted to engage the arms of said shaft, a trigger bar connected to said lever, and means for normally holding the bracket of said lever 115 out of retracting engagement with said shaft 120 arms.

4. In an alarm device, the combination with a cartridge holder, of a firing lever, means tending to force said lever into engagement with a cartridge, a latch for holding said lever retracted, arms secured to said latch and projecting radially therefrom, a bracket mounted for oscillation adjacent said latch and having radially disposed arms, the said bracket being capable of os- 125 130

- cillating in directions at right angles to each other, the said bracket arms being adapted to contact and force said latch arms into retracted position, and a trigger connected 5 to said bracket for rocking the latter.
5. In an alarm device, the combination with a cartridge holder, of a firing lever, means tending to force said lever into engagement with the cartridge, a latch for 10 holding said lever retracted, arms secured to said latch and projecting radially therefrom, a bracket mounted for oscillation adjacent said latch and having radially disposed arms, the said bracket arms being 15 adapted to contact and force said latch arms into retracted position, a trigger connected to said bracket for rocking the same, and the said trigger being capable of oscillating in directions at right angles to each other.
- 20 6. In an alarm device, the combination with a cartridge holder, of a firing lever, means tending to force said lever into engagement with a cartridge, a latch for holding said lever having arms projecting radially therefrom, a bracket having a plurality 25 of radially disposed arms, a lever pro-
- jecting forwardly from said bracket, a block mounted for rocking movement, the said lever being pivoted to said block, the arms on said bracket being adapted upon rocking 30 movement of the latter to engage the arms of said latch to move the latter to retracted position, and a trigger rod connected to said lever.
7. In an alarm device, the combination 35 with a cartridge holder, of a hammer adapted when released to engage and detonate a cartridge, a latch for holding said hammer in retracted position, radially arranged arms on said latch, a tilttable bracket adjacent said 40 latch, arms on said bracket adapted to engage those of said latch to force the latter to retracted position, a trigger rod connected to said bracket, and the said rod being capable of moving in directions at right angles 45 to each other.

In testimony whereof I affix my signature in presence of a witness.

ALPHONSE FERNANDEZ.
